(57) **CLAIM**

The ornamental design for a selfiano, as shown and described.

DESCRIPTION

FIG. 1 is a top, left, rear perspective view of a selfiano showing my new design with the telescopic arm in an extended state;

FIG. 2 is a top, left, front perspective view of the selfiano of FIG. 1;

FIG. 3 is a left side view of the selfiano of FIG. 1;

FIG. 4 is a bottom view of the selfiano of FIG. 1;

FIG. 5 is a top view of the selfiano of FIG. 1;

FIG. 6 is a right side view of the selfiano of FIG. 1;

FIG. 7 is a bottom, left, rear perspective view of the selfiano of FIGS. 1-6 with the telescopic arm in a retracted state;

FIG. 8 is a top, left, front perspective view of the selfiano of FIG. 7;

FIG. 9 is a right side view of the selfiano of FIG. 7;

FIG. 10 is a bottom view of the selfiano of FIG. 7;

FIG. 11 is a left side view of the selfiano of FIG. 7;

FIG. 12 is a top view of the selfiano of FIG. 7;

FIG. 13 is a rear view of the selfiano of FIG. 1 with the telescopic arm in an extended state, with the telescopic arm in a retracted state being identical; and,

FIG. 14 is a front view of the selfiano of FIG. 1 with the telescopic arm in an extended state, with the telescopic arm in a retracted state being identical.

1 Claim, 4 Drawing Sheets
